(57) **CLAIM**

The ornamental design for a light emitting diode lighting fixture, as shown and described.

DESCRIPTION

FIG. 1 is a front elevation view of the light emitting diode lighting fixture showing our new design in accordance with a first embodiment of the present invention;

FIG. 2 is a top plan view thereof, the bottom plan view being a mirror image;

FIG. 3 is a left side elevation view thereof, the right side elevation view being a mirror image;

FIG. 4 is a rear elevation view thereof;

FIG. 5 is a front elevation view of the light emitting diode lighting fixture showing our new design in accordance with a second embodiment of the present invention; and,

FIG. 6 is a front elevation view of the light emitting diode lighting fixture showing our new design in accordance with a third embodiment of the present invention.

In the second and third embodiments of the design, the sides not shown are the same as that shown for the first embodiment except that the dimensions are consistent with the outlines shown in FIGS. 5 and 6, respectively.
